CLAIM

The ornamental design for a case for smart phone, as shown and described.

DESCRIPTION

FIG. 1 is a front perspective view of a case for smart phone showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region from FIG. 2;

FIG. 10 is an enlarged detail view of the encircled region from FIG. 4; and,

FIG. 11 is a cross-sectional view taken along the line 11-11 of FIG. 4.

The dash-dot broken line circle in FIGS. 2, and 4 delineates a portion of the case for smart phone that is part of the claimed design and that is shown on an enlarged scale in FIG. 9, and FIG. 10. The broken lines throughout the drawing figures depict portions of the case for smart phone that form no part of the claimed design. The broken lines and regions bounded by broken lines form no part of the claimed design.
